UNITED STATES PATENT OFFICE

159,705

HOBBYHORSE OR SIMILAR ARTICLE

Minna R. Whitney, Upperville, Va.

Application June 1, 1949, Serial No. 2,985

Term of patent 14 years

(Cl. D34—15)

To all whom it may concern:

Be it known that I, Minna R. Whitney, a citizen of the United States, residing at Upperville, in the county of Fauquier, State of Virginia, have invented a new, original, and ornamental Design for a Hobbyhorse or Similar Article, of which the following is a specification, reference being had to the accompanying drawing, forming part thereof.

The side, not shown, of the hobbyhorse or similar article has substantially the same appearance as the side shown in Fig. 1.

The broken line showing of a man's leg and knee is for illustrative purposes only.

I claim:

The ornamental design for a hobbyhorse or similar article, as shown and described.

MINNA R. WHITNEY.
